UNITED STATES PATENT OFFICE.

FRANK A. BONENBERGER, OF LOUISVILLE, KENTUCKY.

COIN-CONTROLLED MACHINE.

1,384,230.

Specification of Letters Patent. Patented July 12, 1921.

Application filed July 3, 1920. Serial No. 393,959.

To all whom it may concern:

Be it known that I, FRANK A. BONENBERGER, a citizen of the United States of America, residing at Louisville, in the county 5 of Jefferson and State of Kentucky, have invented certain new and useful Improvements in Coin-Controlled Machines, of which the following is a specification.

This invention relates to coin-controlled 10 devices and has special reference to a coin-controlled machine for vending paper towels and the like.

One important object of the invention is to improve and simplify the general construction of devices of this character.

A second important object of the invention is to provide an improved form of coin-receiving driving gear for such apparatus.

A third important object of the invention 20 is to provide an improved feed and cut-off arrangement for use in connection with such an apparatus.

With the above and other objects in view, as will be hereinafter apparent, the invention 25 consists in general of certain novel arrangements of details and combinations of parts hereinafter fully described, illustrated in the accompanying drawings and specifically claimed.

30 In the accompanying drawings, like characters of reference indicate like parts in the several views, and:—

Figure 1 is a perspective view of the exterior of a towel bending apparatus constructed in accordance with this invention.

35 Fig. 2 is a vertical transverse section through the device.

Fig. 3 is a section on the line 3—3 of Fig. 2.

Fig. 4 is a detailed perspective view of 40 a portion of the driving gear.

Fig. 5 is a similar view showing the coin block removed from the driving gear.

Fig. 6 is a similar view of the stop for the driving gear.

45 In the embodiment of the invention herein illustrated there is provided a casing 10 having a hinged door 11, the latter being equipped with the usual lock the key hole of which is indicated at 12.

50 Extending through this casing is an axle 13 having on its outer end a crank-handle 14 while on its inner end there is provided a main driving gear 15 which has on the face next the casing one or more pockets 16 opening peripherally through the gear and having located therein a coin-receiving block 17

provided with a coin recess 18. This block in each instance is secured in the pocket by suitable screws 19. Thus when a block becomes worn it may be readily replaced without the necessity of replacing the entire gear and blocks may be changed from time to time to accommodate different sizes and consequent values of coins. In the side of the casing adjacent the upper side of the 60 peripheral gear 16 is a recess 20 wherein is mounted a stop having a head 21 corresponding in shape and size to the recess 18 and having its upper edge beveled as at 22. This stop is provided with a stem 23 which is surrounded by a spring 24 so that the stop is normally pressed outward to enter the recess 18. When in this position the stop terminates rotations of the gear 15. On the 65 face of the casing and extending therefrom there is provided a coin-receiving slot 25 which terminates inwardly in a chute 26 the lower end of which stops above the stop 21 so that when a coin is dropped down this chute it will come to rest on the beveled edge 23 of the stop 21. Above this end of the 70 chute is provided a guide 27 wherein operates a vertical plunger 28 actuated by a lever 29 the handle of which projects through a slot 30 in the face of the casing. This lever 75 and plunger are normally kept raised by a suitable spring 31. By means of this arrangement when a coin is dropped down the chute and the lever 29 depressed the coin is forced against the beveled edge 23 of the 80 stop 21 and thus causes the head of the stop to move inward, the coin passing into the recess 18 previously occupied by the stop. The crank 14 can now be manipulated to 85 rotate the gear 15 and if there be but one 90 stop as in the case of selling an article for a single coin such as a cent a complete revolution may be effected and when completed further movement will be terminated by the reentry of the stop into the recess 18. However, two or more recesses may be used so 95 that the towel or other article may be sold for two or more cents for instance. In this case when a partial revolution of the wheel has been effected the stop will again check 100 the motion and the complete revolution can be effected by again dropping a coin.

At each side of the casing there is provided a bearing, one of these bearings being shown at 32 and the other not being shown. 110 Extending between these bearings is a shaft 33 whereon is mounted a roller 34 of paper

towels or the like. The paper from this roller passes over small rollers 35 so that it passes immediately back of a glazed window 36 in the front of the pockets and can there be observed. From the lowermost of these small rollers 35 the paper passes between two rubber rollers 37 and 38, the roller 37 being held in fixed bearings while the roller 38 has a limited lateral movement and is 10 pressed against the roller 37 by means of a yoke 39 and spring 40 as clearly shown in Fig. 2. The roller 37 is moreover provided with gear teeth 41 which mesh with the teeth of the gear 15 so that when the latter is rotated the roller will be rotated and the paper will be fed downward between said rollers 37 and 38.

At 42 is a paper chute which terminates at the bottom in a slot 43 opening through 20 the bottom of the casing 10. At one side of this slot is a metallic plate 44 while on the other side is a movable metallic plate 45 which is carried at each end on the lower end of a bell crank lever 46. This lever is 25 normally held in such position that the plate 45 presses towel against the plate 44 thus enabling the paper to be torn off sharply at this point, this pressure being effected by a spring 48. However, it would be impossible 30 to feed the paper through the slot with the plates 44 and 45 pressed together and in order to release the plate 45 from the plate 44 there is mounted on the gear 15 a cam 49 against which the remaining end of the bell 35 crank lever 46 engages, this cam is so shaped that whenever the feeding of the paper has been completed the end of the lever engaging the cam rises and the plate 45 moves toward the plate 44 but whenever the gear 40 15 is rotated the end of the lever engaging the cam is depressed and the plate 45 moves away from the plate 44.

The usual removable coin receptacle 50 is provided.

45 In order to hold the paper roller against wrinkling a suitable spring and presser bar indicated at 51 is provided.

In general operation the coin is deposited, the lever 29 depressed, and the 50 crank 14 rotated. This causes rotation of the roller 37 and movement of the plate 45 away from the plate 44. The paper is thus fed downward from the bottom of the casing until the proper amount has passed through. 55 At this time the parts will resume their original position and the paper can be torn off.

In order to prevent backward rotation

accidentally of the gear 15 a suitable pawl 52 is provided.

60 There has thus been provided a simple and efficient device of the kind described and for the purpose specified.

Having thus described the invention, what is claimed as new, is:—

1. In a device of the kind described, a rotatable wheel having a pocket at its periphery, a member fitting said pocket removably and having a recess therein adapted to receive and hold a coin, and means to hold said member releasably in position in said pocket.

2. In a device of the kind described, a delivery mechanism driving wheel having a coin-receiving recess in one face thereof and opening outwardly of the periphery, a 75 spring pressed stop normally fitting said recess to hold the wheel from rotation, said stop having a beveled portion disposed adjacent the periphery, means to rotate the wheel, and means to force a coin against the 80 beveled portion of the stop and into said recess whereby the stop is forced outward and the wheel freed for revolution.

3. In a device of the kind described, a delivery mechanism driving wheel arranged 85 to be revolved and having a coin receiving recess in one face thereof, a spring pressed stop normally fitting said recess to hold the wheel from rotation, said stop and wheel being constructed and arranged to provide a 90 wedge shaped pocket at one end of the stop, a coin delivery chute leading to the wedge shaped pocket, and means to force a coin from said chute into said pocket and thereby cause retraction of the stop from the 95 recess.

4. In a device of the kind described, a delivery mechanism driving wheel arranged to be revolved and having a coin receiving recess in one face thereof, a spring pressed 100 stop normally fitting said recess to hold the wheel from rotation, said stop and wheel being constructed and arranged to provide a wedge shaped pocket at one end of the stop, a coin delivery chute leading to the wedge 105 shaped pocket, a plunger movable toward and from said recess and engageable with a coin in position opposite to the pocket, and a manually operable lever controlling said plunger, said plunger and lever constituting means to force a coin between the stop and wheel whereby to cause retraction of the stop from the recess.

110 In testimony whereof I affix my signature.

FRANK A. BONENBERGER.
